DESK PAD STRUCTURE

Arthur Cohn, New York, N. Y.

Application August 19, 1946, Serial No. 691,563

2 Claims. (Cl. 120—1)

1

This invention relates to improvements in desk pad structures.

In its broadest aspect the present invention aims at the combination of several desk items (telephone register, appointment book, calendar, memorandum pad, and other accessories) with a desk pad, which items are so coordinated to the latter that convenient and easy conduct of office business will be facilitated and manipulation of at least some of said items needed at one end the same time may be had by one hand only of a person.

It is known that many inconveniences result from the fact that such desk items are often scattered over office desks. Sometimes, one hand of a person is holding the telephone receiver while the other hand of said person must reach for notes or other papers, which mostly do not lie at their usual locations on the desk.

As a further disadvantage may be considered that telephone index devices and similar usually small desk articles or accessories now in use, are likely to be removed from, misplaced or arranged on the desk so that it is difficult to grasp those small articles, when needed, to keep the same all the time in their proper place on the desk, to allow manipulation of the pages of an item, such as a book, a loose leaf index or the jotting down of telephone numbers, appointments, etc.

The present invention eliminates these and other disadvantages and proposes a desk pad which is constructed in a new and clearly arranged manner.

It is therefore one of the objects of this invention to provide means affording easy and quick operation of the desk pad made in accordance with this invention, permitting production thereof at relatively low cost and contributing to maintaining the desk pad in orderly condition and aesthetic appearance.

It is a further object of this invention to provide means rendering possible easy interchangeability of the items used in connection with the new desk pad.

Still another object of the present invention is to provide means allowing the operation and use of the desk pad in the usual manner, although improving the same to such a degree that its usefulness will be considerably enhanced by making available for ready employment all the items or accessories ordinarily considered desirable in connection with an office desk.

Yet, a further object of the invention is to provide means assuring simple and durable construction of the desk pad whose capacity to hold pa-

2

pers, memoranda and other stationery items is increased without producing unsightly and bulky structures and substantially maintaining neat and well arranged disposition of the usually needed items, which may be hidden from view at any time, if desired.

These and other objects and advantages will become more clear from the ensuing specification and drawings, in which:

10 Fig. 1 is a top plan view of the desk pad made in accordance with this invention and shown in open condition;

Fig. 2 is a cross-sectional view taken along line 2—2 of Fig. 1;

15 Fig. 3 is a cross-sectional view on an enlarged scale taken along line 3—3 of Fig. 1;

Fig. 4 is a top plan view of the desk pad shown in Fig. 1 in closed condition;

20 Fig. 5 is a perspective view of one of the accessories used in connection with the desk pad;

Fig. 6 is a perspective view of another of the accessories employed in the desk pad of this invention.

25 Referring now more particularly to the attached drawings, there is disclosed in Figs. 1 and 4 a desk pad 10 in open and closed condition, respectively. Desk pad 10 has a flat backing or support 11 preferably made of cardboard, paste board or similar mass, which may be lined with a soft textile material (not shown) as it is conventional.

30 Desk pad 10 has a median portion 12 and end portions 14 and 15, said median portion carrying on its upper face blotter means 13. End portions 14 and 15, respectively, consist of fixed frame sections 16, 18 and flap sections 17, 19, which are hinged at 20, 21 so that sections 17 and 19 may be swung into superposed position and juxtaposition with respect to fixed sections 16, 18.

35 Fixed sections 16, 18 are provided with upper loops 22, 23 and with lower loops 24, 25 and further with pockets 26, 27. The aforesaid loops and pockets 22 to 27 are either directly mounted on support 11 or respectively by means of an intermediate base 28 adhesively fixed or glued on the top surface of support 11.

40 As can be seen from Figs. 1 and 3, base 28 of each of the fixed sections 16, 18 provides opposed pockets 30, 31 with respect to support 11 for the insertion of the lateral ends of the blotter 13 and for removal therefrom.

45 The fixed sections 16, 18 are connected by respective hinges 20, 21 preferably made from leather to the flap sections 17 and 19. To this

effect one end of each leather hinge **20a**, **21a** is fixed on support **11** (either by adhesives or stitching), whereas the opposite ends **20b**, **21b** of said leather hinges extend over the outer surface of the respective flap sections **17**, **19** and form the outermost leather binding or cover therefor, so that when flaps **17**, **19** are respectively swung into closed positions of the desk pad **10**, the leather binding or layer **17a**, **19a** come to lie on top of end portions **14** and **15**.

Swingable flap sections **17** and **19** are also provided with upper loops **32**, **33** and lower loops **34**, **35** and with suitable pockets **36**, **37**. As can be seen from Fig. 1, opposed loops **22**, **32** and **23**, **33**, as well as **24**, **34** and **25**, **35** may be located in alignment with each other, respectively, and are preferably employed for the insertion of book- or folderlike units, such as telephone register or index devices **36**, **37**, and ring-book device **38**.

As can be seen from Fig. 5, the folderlike telephone register device **37** consists of carrier sheet **39** terminating into outwardly extending reduced portions **40**, **41** and of pages **42**, **43** connected with said carrier sheet **39**. As can be realized from Fig. 5, page **42** is hinged at **44** to page **43** of the telephone register device.

The pages **42** and **43** are co-extensive with each other, while the outwardly extending portions **40** and **41** are so shaped (preferably tapered) as to facilitate insertion of the device **37** within upper and lower end loops **22** and **24**. It is well understood that the structure of the telephone register device **36** is similar to that of the just described register device **37** and is inserted by means of its extensions **50**, **51** within upper and lower loops **32**, **34**.

Ringbook device **38** consists of the two carriers or supports **52**, **53** having the upper extensions **52a**, **53a** and the lower extensions **52b**, **53b**, respectively. Carriers **52** and **53** are hingedly connected with each other by means of a spiral wire element **54** threaded through perforations (not shown) of the carriers **52** and **53**.

Element **54** threadedly engages the sheets **55** of a memorandum pad **56**, so that the sheets may be moved in a ring binder fashion about the element **54**.

As can be seen from Fig. 1, device **38** may be removably connected to the desk pad by inserting extension portions **53a** and **53b**, respectively, into upper and lower loops **33** and **35** and by further inserting the extension portions **52a** and **52b** into upper and lower loops **23** and **25** said upper loops **23**, **33** and lower loops **25**, **35** being respectively disposed adjacent the upper and lower ends of said fixed section **18** and said flap section **19**.

It will be observed, that extensions **52a** and **52b** are shorter in width than the loops **23** and **25**, and that they are also shorter in width than the extensions **53a** and **53b**. This structure is necessitated in order to bring about actuation (opening and closing) of the ringbook device **38**, while the swingable flap section **19** is moved relatively to the fixed section **18**.

Thus a sliding movement of the extensions **52a** and **52b** lengthwise of the respective loops **23** and **25** will be had, so that in closed position, indicated by dot-dash lines in Fig. 3 of the swingable flap **19**, the pages **55** of the structure **38** will assume a position within the boundary of the closed end portion **15**, as may be also realized from Fig. 4.

As indicated in Fig. 1, pockets **26** and **27** may

be used for receiving loose notes, business cards, and the like. Pocket **31**, in this instance, is employed to hold a paper pad **57**, whereas pocket **36** is provided with a window **58** to expose to view a calendar **59**.

As may be seen from the above explanations, the outside appearance of the desk pad made in accordance with this invention is substantially the same as that of the conventional desk pads. However, the commonly known end portions on the opposite sides of the pad, which generally are employed to retain the sheet of blotting paper, have been advantageously improved by means of a new construction which permits the new desk pad to be provided with means for carrying and making accessible many desirable desk accessories, which may be hidden from view in closed position of the new desk pad. The result achieved by this invention is that the aesthetic appearance of the desk pad is maintained and that the same neither becomes bulky nor unsightly.

When the end portions of the desk pad are employed to carry a telephone register, the latter is preferably composed of several independent folders (Fig. 5), on which blank spaces and/or lines for telephone numbers, addresses etc. may be provided according to the needs of the user.

Register devices **36** and **37** are constructed so that they may be moved in opposite directions when flap section **17** assumes a superposed position relatively to fixed section **16** in closed condition of end portion **14**. The aforesaid register devices may be easily folded and moved without interference with each other. If desired, these register devices **36** and **37** may be reinforced by cardboard or other stiffening means which facilitate convenient handling and ready replacement of the folders and reduces further the wear thereof to a high degree.

The above mentioned ring-binder device **38** is held at its upper and lower ends in a similar manner as the aforesaid register devices **36**, **37**.

If the device **38** is to be used as an appointment book, in which case it will have necessarily more than 52 pages, the same must be opened and closed without any inconvenience when movements of the flap section **19** occur. Such book must also be retained in position within fixed section **18** and movable flap section **19**.

Relatively stiff material for the carriers **52**, **53** (pressboard, heavy acetate sheets, etc.) assure suitable support for such appointment book and simultaneously an appropriate connection between parts **18**, **19** of the end portion **15**, so that the swingable flap section **19** will be kept taut and straight without causing any warping or distortion for said flap section or fixed section.

On account of the particular construction the cover or carriers of said ring-binder book are prevented from being shifted from their positions and hold the book in proper place, so that when the flap is opened, the book presents itself in open condition, while its pages can be turned over very easily and facilitate writing thereon.

The desk pad is so constructed that its parts, which are to be carried by it, are interchangeable and can be easily replaced and attached at the right or left flap section and vice versa, following the individual habits of the user.

As a particular advantage of the new desk pad is to be mentioned the fact that it assumes in open condition a substantially flat unit (Fig. 2) which extends throughout its whole length over a table or desk surface and which is devoid of

any overhanging parts which would otherwise lead to deformation, warping and unsightliness of the said pad.

It can thus be seen, that there has been achieved in accordance with this invention a desk pad structure which consists of a substantially flat support having two lateral end portions and an intermediate or median portion for carrying the blotter in sheet formation, said lateral end portions being each provided with a fixed section and a flap section, ends of said fixed sections facing each other forming lips on said median portion and being engageable with said blotter sheet to retain the same in position on said median portion, hinge means connecting each flap section with a respective fixed section, whereby said flap sections may be swung to juxtaposition and superposed position relatively to said fixed sections, respectively, said hinge means being made of leather material, said material extending from below said fixed sections to the surface of said flap sections, respectively, and forming a top cover for said flap sections, whereby said hinge means in juxtaposition of said fixed sections with said flap sections extend substantially in alignment with and at the level of said flat support, and loop means for retaining flat articles disposed at said fixed sections and at said flap sections, respectively, said retaining means being hidden from view in superposed position of said flap sections with said fixed sections.

While there has been shown and described and pointed out the fundamental novel features of the invention as applied to the above embodiment, it will be understood that various omissions, substitutions and changes in the form and details of the desk pad illustrated and its operation may be made by those skilled in the art without departing from the spirit of the invention.

Having thus described the invention what is claimed as new and desired to be secured by Letters Patent is:

1. In a device of the character described, having a lateral end with a fixed section and a flap section, means hingedly connecting said flap section to said fixed section, whereby said flap section may be swung into superposed position and in juxtaposition to said fixed section; an upper loop and a lower loop arranged on each of said fixed section and of said flap section, carrier means supporting paper sheets, each carrier means being provided with a pair of extensions projecting beyond said paper sheets, upper extension and lower extensions, respectively, said upper extension being, respectively, engageable with said upper loops, said lower extensions being, respectively, engageable with said lower loops,

whereby said carrier means may be removably and interchangeably disposed on said flap section and on said fixed section, and means swingably connecting said paper sheets to one another and to said carrier means, one pair of said extensions of said carrier means being smaller in width than the width of each of said upper and lower loops, whereby said one carrier means may slide within their respective loops relatively to the other pair of said extensions, said other pair of extensions being engaged by said upper and lower loops of said flap section and being movable with the latter to open and closed position of said carrier means, respectively, when said flap section is moved to said juxtaposition and said superposed position, respectively.

2. In a device of the character described having a fixed section and a flap section, hinge means connecting said flap section with said fixed section, whereby said flap section may be swung to juxtaposition and superposed position relatively to said fixed section, respectively, a book structure having cover means, extensions on said cover means, leaves connected through a spiral wire element with said cover means, and means for engaging said extensions of said cover means and respectively disposed at said fixed section and at said flap section, said extensions being smaller in width than said engaging means, whereby said cover means of said book structure are slidably coupled with said sections and will follow the movement of said flap section to said juxtaposition and superposed position, respectively.

ARTHUR COHN.
